UNITED STATES PATENT OFFICE

2,670,931

APPARATUS FOR DRILLING HOLES FOR
ROOF ANCHORS

John C. Curtis, Claremont, N. H., assignor to Joy
Manufacturing Company, Pittsburgh, Pa., a
corporation of Pennsylvania

Application January 20, 1950, Serial No. 139,612

16 Claims. (Cl. 255—51)

1

This invention relates to mobile drilling apparatus and more particularly to an improved mobile drilling apparatus especially designed for use in drilling upright roof holes in underground mines or tunnels, for receiving roof anchors.

In mines or tunnels where roof control is effected by internal suspension type roof anchors which are set in the roof strata, upright holes are usually drilled in the roof for receiving the anchors. In underground mines or tunnels where head room is relatively low, roof hole drills of known types are too great in length to enable roof drilling in the restricted spaces encountered, and particularly when conventional stoper type rock drills are employed for drilling the roof holes the head room must be relatively high to accommodate the drills. In roof drills of other known types the drills are relatively heavy and complicated and while certain types may operate where relatively low head room is present they are relatively expensive and usually require more than one operator, thereby increasing the cost of roof control. The present invention contemplates improvements over such known types of roof hole drills in that a relatively simple and compact drill structure is provided which is readily mobile and which may be operated by a single operator, and due to its vertical compactness may drill upright roof holes of substantial depth in mines or tunnels having low head room. Thus the cost of drilling roof holes in low coal or in tunnels having low head room may be maintained at a minimum. The drill of the present invention is of the pneumatic impact type mounted on a mobile base and has a pneumatic feeding mechanism which while retaining vertical compactness provides a relatively long range of feed thereby avoiding the need of frequent steel changes. The drilling apparatus of the present invention is readily mobile and may be easily transported about the mine or tunnel and quickly set up in drilling position, and the drilling tool is firmly supported during the drilling operation.

An object of the present invention is to provide an improved drilling apparatus of a readily mobile and compact construction. Another object is to provide an improved drilling apparatus for drilling upright roof bolt holes in the roof strata of underground mines or tunnels. Yet another object is to provide an improved drilling apparatus of the pneumatic impact type which is extremely vertically compact and which has a relatively long range of vertical feed for its height thereby enabling use of the drill in

2

mine passageways or tunnels having head room of varying heights. A further object is to provide an improved mobile mounting for a pneumatically fed hammer drill of comparatively short length and having an auxiliary feeding means whereby the feeding travel of the drill may be materially lengthened. A still further object is to provide an improved drilling apparatus having a pair of feeding devices which may act cumulatively to provide a relatively long feeding travel of the drilling implement. Still another object is to provide an improved rock drill feeding mechanism of the pressure fluid actuated cylinder and piston type wherein a plurality of coaxial cylinder and piston devices, arranged and mounted in a novel manner, are employed. A further object is to provide an improved rock drill feeding mechanism of the multi-cylinder type wherein the feed cylinders may cooperate to feed the drilling tool toward the work, thereby cumulatively to provide a relatively long feeding travel. Still another object is to provide an improved hammer rock drill of the wheel mounted stoper type. These and other objects and advantages of the invention will, however, hereinafter more fully appear.

In the accompanying drawings there is shown for purposes of illustration one form which the invention may assume in practice.

In these drawings:

Fig. 1 is a plan view of a roof anchor hole drill constructed in accordance with an illustrative embodiment of the invention.

Fig. 2 is a side elevational view of the drilling apparatus shown in Fig. 1, with a part of the carriage frame broken away and indicating the transport position of the apparatus in dotted lines.

Fig. 3 is an end view of the drill apparatus shown in Figs. 1 and 2, with a laterally tilted position of the drilling tool indicated in dotted lines.

Fig. 4 is a detail vertical sectional view taken on line 4—4 of Fig. 5, showing the secondary feed for the drilling tool.

Fig. 5 is an enlarged vertical sectional view taken on line 5—5 of Fig. 1, showing the drilling tool in position preparatory to drilling.

Fig. 6 is a detail vertical sectional view taken on line 6—6 of Fig. 5.

Fig. 7 is a detail sectional view taken on line 7—7 of Fig. 5.

Fig. 8 is a side elevational view with the near wheel removed, showing the primary and sec-

ondary feeds in fully extended positions, where head room is high.

Fig. 9 is a side elevational view similar to Fig. 8, showing the primary feed in extended position and with the secondary feed retracted, under low head room.

In this illustrative embodiment of the invention an improved mobile drilling apparatus is provided for drilling upright holes in the roof strata of a mine passageway, tunnel or other subterranean excavation, for receiving anchor bolts of suspension type roof supports. While the drilling apparatus disclosed is especially designed for use in drilling upright holes in the roof, evidently, holes may be drilled at other locations and features of the invention may be embodied in drilling tools of other types.

The improved drilling apparatus, as shown in the drawings, comprise a mobile base 1 in the form of a two-wheeled carriage having a generally L-shaped, open-sided frame 2 herein desirably of a fabricated, welded, tubular construction. The frame 2 includes a longitudinal tubular side portion 3 and a transverse end portion 4, and the latter includes U-shaped frame portions or wheel-yokes 5 each carrying an axle 6 on which a rubber-tired wheel 7 is journaled. The side frame portion 3 is welded to one of the U-shaped axle frames 5 and the transverse portion 4 includes a transverse cylindrical bar or cross tube 8 extending horizontally between and welded to the U-shaped axle frames 5. The cross bar 8 is arranged parallel with the wheel axes in the manner shown. The longitudinal side frame portion 3 of the carriage frame has near its outer end a lateral boss 9 welded to its inner side and arranged in a vertical opening in this boss is an upright rod 10 provided with a handle 11. The rod has a pointed lower end 12 and is adjustable vertically in the boss bore and its pointed end is engageable with the ground or floor as shown in Figs. 2 and 3 for supporting the outer end of the carriage frame. A set screw 13 having an operating handle 14 is threaded within the boss and is adjustable into engagement with the rod for securing the latter rigidly in adjusted position. The handle may be grasped by the operator for tilting the carriage frame into its transport position (as shown in dotted lines in Fig. 2) and for moving the carriage over the ground or floor in an obvious manner. The outer end of the tubular side portion 3 of the carriage frame has a detachable connection 15 with an air supply hose 16 and the side frame due to its tubular construction provides a constant pressure chamber for the pressure fluid supplied to the apparatus, to reduce pressure fluctuations in the air line.

In this illustrative construction, as shown in Figs. 1 and 6, arranged centrally between the ends of the cross bar 8 and located between spaced collars 18 welded to the bar is a pivoted support or clamp 19 which surrounds and is pivotally mounted on the cross bar. One of the collars, as shown in Fig. 7, has a threaded boss 20 for receiving a set screw 21 provided with a pivoted operating handle 22. This set screw acts on a clamping block 23 mounted in a recess 24 in the collar and this block has its inner gripping face engageable with a plane face 25 of a flange 26 on the clamp. The collars 18 have spaced abutment lugs 28 and 29 engageable with a stop pin 30 carried by the clamp for limiting the pivotal movement of the support 19 about the axis of the cross bar as later explained. By tighten-

5

ing the set screw 21 the block 23 may be brought into gripping engagement with the plane face 25 of the clamp for locking the latter in its desired position of adjustment. The clamp-frame has a longitudinal bore 31 which receives a longitudinal bolt 32 having its head 33 engaging the outer surface of a swivel plate 34. The clamp 19 has a plane face 35 with which the inner face 36 of the swivel plate 34 is engageable, and a nut 37 threaded on the bolt, when tightened, moves the faces 35 and 36 into tight frictional engagement to lock the swivel plate 34 in adjusted position about the longitudinal axis of the bolt 32. When the pivoted clamp or support 19 is in its position shown in Fig. 5, with the stop pin 30 engaging the abutment lugs 28 on the spaced collars 18 and with the gripping block 23 set in gripping position, the swivel plate 34 is in the vertical position shown. When the bolt 32 is loosened the swivel plate 34 may be swung in transverse planes about the bolt axis relative to the clamp 19.

The swivel plate 34 has a depending frame portion 39 provided with a step-like bottom portion 40 to which the lower end of a vertical pneumatic feed cylinder 41 is secured, as by welding or otherwise, at 42. Contained in this upright cylinder is a reciprocable feed piston 43 having its piston rod 44 extending upwardly through a packed top head 45 of the cylinder, and this piston rod is rigidly secured at 46 to a cross plate or yoke 47 (Figs. 4 and 5). The cross plate or yoke 47 is connected by side rods 48 which extend downwardly in parallelism along the sides of the feed cylinder 41 and which are secured at 49 to lateral lugs 50 integral with a sliding frame or cross head 51 guided on the exterior periphery of the feed cylinder 41. Secured to the sliding frame 51 is a depending frame portion 53 having a bottom stirrup 54 to which the lower end of a vertical piston rod 55 is rigidly secured at 56. This piston rod extends upwardly through a packed lower head 57 of a reciprocable vertical pneumatic feed cylinder 58 and secured to the upper end of the piston rod 55 is a feed piston 59 contained in the reciprocable feed cylinder. During feed the stirrup 54 has a bottom surface 60 adapted to rest upon the floor or ground surface when the feed piston 43 is in lowered position as shown in Fig. 5. The cylinder 58 is arranged in parallel side by side relation with the cylinder 41, and the cylinder 58 has an upper head 63 provided with a lateral bracket 64 herein desirably formed integral with a front chuck housing 65 of a conventional pneumatic hammer drilling tool generally designated 66. This drilling tool is herein arranged in parallel side by side relation with the feed cylinder 58 and includes a conventional pressure fluid actuated hammer motor having a cylinder 67 secured to the chuck housing and containing a usual hammer piston (not shown) for percussively actuating a drill steel 68. The drill steel 68 has its shank receivable in a conventional chuck within the chuck housing 65 and the upper end of the steel carries a conventional drill bit 69. The motor cylinder has a rear head block 70 secured thereto and this block carries a conventional throttle valve mechanism 71 which is adapted to control fluid flow to the drilling motor and to the two feed cylinders 41 and 58. Projecting laterally from the motor cylinder as shown in Fig. 3 is a handle 72 having a grasping portion 73 which carries a conventional feed vent valve mechanism 74 which is adapted to regulate the feeding pressure in both feed cylinders. A sup-

75

ply pipe 76 has a lateral connection with the tubular side frame portion 3 of the carriage whereby fluid may be conducted from the constant pressure chamber to a pipe 77 which has a detachable connection at 78 with one end of a conventional line oiler or lubricator 79. Detachably connected at 80 with the opposite end of the line oiler is an elbow 81 which has connection at 82 to a flexible hose 83 which leads to the inlet chamber of the throttle valve mechanism 71 in a well-known manner. The throttle valve mechanism controls the flow of pressure fluid through a passage 84 (Fig. 5) which communicates with the upper end of the feed cylinder 58 above the piston 59. The throttle valve mechanism also controls the flow of fluid through a passage (not shown) in the handle 72 which is connected by a flexible hose 85 to a passage 86 (Fig. 5) in the step-portion 40 of the swivel plate 34, and the passage 86 communicates directly with the lower end of the cylinder 41 beneath the piston 43 as shown in Fig. 5. Thus, the throttle valve mechanism 71 may control the fluid supply to both feed devices to effect feed and the vent valve mechanism 73 may effect venting of both feeding devices to regulate the feeding pressure.

When the set screw 21 is loosened to effect release of the clamp block 23 the pivoted support or clamp 19 may be swung about the longitudinal axis of the cross bar 8 to locate the drilling tool in the desired position, and during transport of the apparatus the stop pin 30 on the clamp engages the abutment lugs 29 on the collars 18 to locate the drilling tool in its transport position as indicated in dotted lines in Fig. 2. When the bolt 32 is loosened the swivel plate 34 may be turned about an axis at right angles to the longitudinal axis of the cross bar to locate the frame 30 and drilling tool in the desired lateral tilted position relative to the carriage frame, as indicated in dotted lines in Fig. 3, and the bolt 32 may thereafter be tightened and the gripping block 23 may be set to secure the parts firmly in adjusted position. The drilling tool may be swung horizontally about either of the vertical axes of the parallel feeding devices, and to accomplish this the operator may grasp the handle 72 to effect swinging of the tool with the cylinder 58 about the axis of the piston rod 55 and with the frame 51 about the axis of the feed cylinder 41. The handle 72 may also be grasped by the operator to hold the drilling tool steady during the drilling operation. By arranging the feed cylinders 41 and 58 and the drilling tool in the manner disclosed extreme vertical compactness is attained while by concurrently operating the feed devices a cumulative feed of relatively great length may be provided. By providing the carriage frame with an open side, the operation of the tool is facilitated, particularly when the operator is kneeling on the floor in mines or tunnels having low head room.

The general mode of use of the improved drilling apparatus is as follows:

During transport of the apparatus about the mine or tunnel, the pivoted clamp or support 19 is swung relative to the cross bar 8 into the position shown in dotted lines in Fig. 2, with the feeding means and the drilling tool in substantially horizontal, lowered positions on the carriage, and the operator may hold the carriage frame in raised position from the floor by grasping the handle 72 or the tubular side frame 3 of the carriage so that the apparatus may be rolled along the floor or ground surface. Thus, by

grasping the handle 72 or the tubular side frame 3 of the carriage the drilling apparatus may be readily moved from place to place by the operator even when the head room is relatively low. 5 When it is desired to drill an upright hole in the roof strata the clamp 23 may be released and the clamp or support 19 may be swung about its pivot on the cross bar 8 until the stop pin 30 on the clamp engages the collar-lugs 28 on the cross bar, and thereafter the clamp may be tightened to secure the clamp firmly to the cross bar. By loosening the clamping bolt 32 the swivel plate 34 may be swung in transverse planes about the bolt axis to locate the drilling tool in the 10 desired lateral position, either in a vertical position or in positions inclined with respect to the vertical as desired, and thereafter the bolt 32 may be tightened to lock the parts firmly in position. When the drilling tool is in the vertical drilling 15 position shown in full lines in Figs. 2 and 3, the sliding frame 51 may be lowered relative to the cylinder 41 to bring the bottom surface 60 of the stirrup 54 into engagement with the ground surface or floor as shown in Figs. 5 and 9. The shank of the drill steel 68 may then be inserted 20 in the chuck of the drilling tool with the drill bit 69 located just below the roof level as shown in Fig. 5, when the apparatus is operating under low head room. The fluid supply hose 16, which 25 leads to any suitable source of fluid under pressure, may then be attached by the connection 15 to the outer end of the tubular side frame 3 of the carriage, and the throttle valve mechanism 71 of the drilling tool may then be manipulated 30 to effect fluid supply to the hammer motor to cause percussive actuation of the drill steel 68. When the parts are in the position shown in Fig. 5, with both feeding means fully collapsed as shown, the throttle valve mechanism 71 may 35 be positioned to effect fluid supply through the passage 84 to the feed cylinder 58 and concurrently through the passage in the handle 72 and the hose connection 85 to the feed cylinder 41. The pressure fluid flowing to the feed cylinder 48 above the stationary piston 59 will effect movement of the cylinder upwardly moving the drilling tool therewith thereby to feed the drill steel up toward the roof, and as the drill bit 69 is fed 40 upwardly and as the drill steel is percussively actuated, a vertical hole is drilled in the roof strata as shown in Fig. 9. If the deeper hole is desired under the low head room shown the feeding means may be retracted and a longer drill steel may be substituted for the one shown. 45 50 When the head room is substantially higher as shown in Fig. 8, and the feed cylinder 58 is fully extended, the pressure fluid flowing to the stationary feed cylinder 41 below the feed piston 43 will move the latter upwardly in the cylinder thereby continuing the feeding of the drill bit upwardly as the hole deepens. As the feed piston 43 moves upwardly the feeding device 58, 59, together with the drilling tool, move upwardly therewith and at that time the stirrup 54 no longer rests on the ground surface or floor. The sliding guide frame 51 as it moves along the feed cylinder 41 provides an adequate guide for the drilling tool at this time. In Fig. 8, both feeding means are shown in fully extended position. 55 During the drilling operation the operator may 60 grasp the handle portion of the handle 72 to hold the drilling tool steady, and prior to the starting of the hole the operator may swing the drilling tool laterally into different angular positions about the parallel axes of the feed cylinders 70 75

41 and 58, as shown in full and dotted lines in Fig. 1, to obtain the desired tool location. As the drill bit 69 is fed upwardly toward the work during the drilling operation the vent valve mechanism 74 may be operated to vent fluid from the feed cylinders thereby to regulate the feeding pressure. When it is desired fully to retract the feeding means the throttle valve mechanism 71 may be positioned to cut off the fluid supply to the feed cylinders and the latter may be vented to atmosphere. The two feeding devices, as above described, act cumulatively to effect a long feeding travel of the drill bit, but yet may be collapsed to provide an extremely vertically compact structure well adapted to conditions where the head room is low. Evidently, when upright holes in the roof of greater depth than the height of the mine or tunnel are desired it will be necessary to use sectional drill steel in a well-known manner.

As a result of this invention an improved mobile drilling apparatus is provided which may be readily moved about a mine passageway or tunnel and may be quickly set up into and firmly supported in drilling position. By the provision of the novel feeding structure disclosed, an extremely vertically compact drill is provided especially designed for use in drilling upright anchor holes in the roof strata of a mine passageway or tunnel having relatively low head room. The drilling apparatus is not only readily mobile and extremely vertically compact but is also simple and rugged in design, well adapted to the purpose for which it is intended. By the provision of the primary and secondary feeding means arranged and mounted in the compact manner disclosed a relatively long feeding travel of the drilling tool is attained. The drill structure, due to the novel compact relationship of the two feeding means and the drilling tool, is of no greater height than a standard single feed type hand-held stoker drill which has not more than one-half of the feeding travel of the drill of the present invention. The novel wheeled carriage for the drilling tool provides a stable support for the drilling tool during the drilling operation thereby substantially relieving the operator of the necessity of manually supporting the drill and due to its extremely light weight and compact arrangement the carriage may be readily moved through the restricted spaces encountered in an underground mine or tunnel. These and other manners of use and advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drilling apparatus, a base, a frame carried by said base, a vertical feed cylinder secured at its bottom to said frame, a feed piston reciprocable in said feed cylinder and having its piston rod extending upwardly through the upper end of said cylinder, a frame surrounding and slidably guided on said cylinder, a connection between the upper end of said piston rod and said sliding frame, a piston having its piston rod secured at its lower end to said sliding frame, a re-

ciprocable cylinder containing said last mentioned piston, and a drilling tool carried by said reciprocable cylinder.

5 2. In a drilling apparatus, a drilling tool, a fluid actuated feeding means for said tool comprising a stationary upright cylinder, a piston reciprocable in said cylinder and having its piston rod projecting from said cylinder, a sliding frame guided on said cylinder, connection between said piston rod and said sliding frame, a second piston arranged parallel with said first mentioned piston and having its piston rod secured to said sliding frame, and a reciprocable cylinder containing said last mentioned piston and by which said drilling tool is carried.

10 3. In a drilling apparatus, a drilling tool, and fluid actuated feeding means for said tool comprising a stationary upright feed cylinder, a reciprocable feed piston contained in said cylinder and having its piston rod projecting from the upper end of said cylinder, a sliding frame guided on said cylinder for movement therealong, connections between said piston rod and said sliding frame, said sliding frame having a downwardly projecting step portion, a second feed piston arranged parallel with said first mentioned piston and having the lower end of its piston rod secured to said step portion of said frame, and a reciprocable feed cylinder containing said last mentioned feed piston and by which said drilling tool is carried.

15 4. A drilling apparatus comprising a frame including a horizontal cross frame member, a support carried by said cross frame member and mounted to swing in vertical planes relative thereto, said support having a depending portion extending downwardly below said cross frame member, a vertical feed cylinder secured at its lower end to the bottom of said support portion, a member slidably guided on said feed cylinder for movement longitudinally therealong and having a depending frame portion provided with a bottom stirrup, a piston reciprocable in said vertical cylinder and having its piston rod extending upwardly through the top head of said cylinder, connections between the upper end of said piston rod and said slidably guided member, a parallel piston rod secured at its lower end to said bottom stirrup providing portion of said slidably guided member and having a piston at its upper end, a reciprocable cylinder in which said last mentioned piston is contained, said last mentioned cylinder having an upper head portion, and a drilling tool adapted to actuate a drilling implement and arranged in parallelism with said last mentioned cylinder, said tool having its upper portion secured to the said upper cylinder head portion.

20 5. A drilling apparatus as set forth in claim 4, wherein said stirrup providing portion when said first mentioned piston is in its retracted position engages the ground and said drilling tool when said reciprocable cylinder is retracted is disposed below the top of said first mentioned feed cylinder.

25 6. In a drilling apparatus, a base, a vertically disposed drilling tool, a pair of coacting feeding devices mounted in vertical parallel relation on said base for feeding said tool toward the work, each of said devices being fluid actuated and comprising relatively reciprocable feeding elements, with the reciprocable element of one device supporting said other device, means for supplying pressure fluid to said feeding devices to 30 cause said devices to act cumulatively to feed

9 said tool, and said tool carried by the reciprocal element of said other device at one side of the latter in parallelism therewith, and said tool mounted on said feeding devices to swing freely laterally about either of the parallel vertical axes of said devices, into different lateral drilling positions relative to said base, one of said feeding devices swinging laterally with said tool during swinging of the latter about the vertical axis of said other device.

7. In a drilling apparatus, a base, a vertically disposed drilling tool, a pair of coacting feeding devices mounted in vertical parallel relation on said base for feeding said tool toward the work, each of said devices being fluid actuated and comprising relatively reciprocal feeding elements, with the reciprocal element of one device supporting said other device, means for supplying pressure fluid to said devices to cause said devices to act cumulatively to feed said tool, and said tool carried by the reciprocal element of said other device at one side of the latter in parallelism therewith, and said tool mounted on said feeding devices freely to swing laterally about either the parallel vertical axes of said devices, into different lateral drilling positions relative to said base, one of said feeding devices swinging laterally with said tool during swinging of the latter about the vertical axis of said other device, and said tool having a handle projecting laterally therefrom and adapted to be grasped by the operation for swinging said tool about either of said parallel axes and for holding said tool against such swinging movement about said axes during the drilling operation.

8. In a drilling apparatus, the combination comprising a supporting frame, a vertical feed cylinder mounted on said frame, a piston reciprocal in said cylinder and having a piston rod projecting from said cylinder at one end thereof, a ground engaging bottom support having connection with the projecting end of said piston rod whereby said piston may raise and lower said bottom support with the latter guided during its movement by said cylinder, said support when said piston is retracted resting directly upon the ground, a piston rod arranged in parallelism with said first mentioned piston rod and secured at its lower end to said bottom support, a reciprocal feed cylinder in which said last mentioned piston is contained, a drilling tool adapted to actuate a drilling implement and arranged in parallel side by side relation with said reciprocal cylinder and secured to the latter with the upper ends of said reciprocal cylinder and said tool substantially coplanar at right angles to the direction of feed of said tool, and means for supplying pressure fluid to said cylinders to cause said reciprocal piston and said reciprocal cylinder cumulatively to effect feed of said tool.

9. A drilling apparatus as set forth in claim 8 wherein, when said support is resting against the ground and said reciprocal cylinder is retracted, said reciprocal cylinder has its upper end disposed a substantial distance in advance of the lower end of said first mentioned cylinder and the upper end of said reciprocal cylinder moving upwardly above the upper end of said first mentioned cylinder when said reciprocal cylinder is in its most advanced position.

10. In a drilling apparatus, the combination comprising a frame, a vertical fluid cylinder secured at its lower portion to said frame, a pis-

ton reciprocal in said fluid cylinder and having its piston rod extending upwardly through the upper end of said cylinder, a frame guided on said cylinder for movement longitudinally therewith, a connection between the upper end of said piston rod and said guide frame, a piston having its piston rod secured at its lower end of said guide frame, a reciprocal fluid cylinder containing said last mentioned piston, and a drilling tool carried by said reciprocal cylinder and adapted to actuate a drilling implement.

11. In a drilling apparatus, the combination comprising a drilling tool adapted to actuate a drilling implement, fluid actuated means for moving said tool in a vertical direction comprising a stationary upright fluid cylinder, a piston reciprocal in said cylinder and having its piston rod projecting from said cylinder, a frame guided on said cylinder for movement longitudinally therewith, connections between said piston rod and said guide frame, a second piston arranged parallel with said first mentioned piston and having its piston rod secured to said guide frame, and a reciprocal cylinder containing said last mentioned piston and by which said drilling tool is carried.

12. In a drilling apparatus, the combination comprising a drilling tool adapted to actuate a drilling implement, and fluid actuated means for moving said tool axially in a vertical direction comprising a stationary upright fluid cylinder, a reciprocal piston contained in said cylinder and having its piston rod projecting from the upper end of said cylinder, a frame guided on said cylinder for movement longitudinally therewith, connections between said piston rod and said guide frame, said guide frame having downwardly projecting step portion, a second feed piston arranged parallel with said first mentioned piston and having the lower end of its piston rod secured to said step portion of said guide frame, and a reciprocal fluid cylinder containing said last mentioned piston and by which said drilling tool is carried.

13. A drilling apparatus comprising, in combination, a support, a frame adjustably mounted on said support and having a depending portion, a vertical fluid cylinder secured to said depending frame portion, a member guided on said cylinder for movement longitudinally therewith and having a depending frame portion provided with a bottom stirrup, a piston reciprocal in said vertical cylinder and having its piston rod operatively connected to said guided member, a parallel piston rod secured at its lower end to said bottom stirrup providing portion of said guided member and having a piston at its upper end, a reciprocal cylinder in which said last mentioned piston is contained, and a drilling tool for actuating a drilling implement and arranged in parallelism with said last mentioned cylinder, said tool having its upper portion secured to the upper portion of said last mentioned cylinder.

14. A drilling apparatus as set forth in claim 13 wherein said stirrup providing portion, when said first mentioned piston is in its lowermost retracted position in said vertical cylinder, engages the ground and said drilling tool, when said reciprocal cylinder is retracted, is disposed below the top of said first mentioned cylinder.

15. In a drilling apparatus, the combination comprising a supporting frame, a vertical fluid cylinder mounted on said frame, a piston reciprocal in said cylinder and having a piston rod

11

projecting from said cylinder at one end thereof, a ground engaging bottom support having connection with the projecting end of said piston rod whereby said piston may raise and lower said bottom support with the latter guided during its movement by said cylinder, said bottom support when said piston is lowered in said cylinder resting directly upon the ground, a piston rod arranged in parallelism with said first mentioned piston rod and secured at its lower end to said bottom support, a reciprocable fluid cylinder in which said last mentioned piston is contained, a drilling tool adapted to actuate a drilling implement and arranged in parallel side by side relation with said reciprocable cylinder and secured to the latter with the upper ends of said reciprocable cylinder and said tool at substantially the same level, and means for supplying pressure fluid to said cylinders to cause said reciprocable piston and said reciprocable cylinder cumulatively to effect axial movement of said tool.

16. A drilling apparatus as set forth in claim

12

15 wherein, when said bottom support is resting against the ground and said reciprocable cylinder is retracted, said reciprocable cylinder has its upper end disposed a substantial distance above the lower end of said first mentioned cylinder, and the upper end of said reciprocable cylinder moving upwardly above the upper end of said first mentioned cylinder when said reciprocable cylinder is in its most advanced position.

JOHN C. CURTIS.

16. A drilling apparatus as set forth in claim 15 wherein, when said bottom support is resting against the ground and said reciprocable cylinder is retracted, said reciprocable cylinder has its upper end disposed a substantial distance above the lower end of said first mentioned cylinder, and the upper end of said reciprocable cylinder moving upwardly above the upper end of said first mentioned cylinder when said reciprocable cylinder is in its most advanced position.

17. A drilling apparatus as set forth in claim 15 wherein, when said bottom support is resting against the ground and said reciprocable cylinder is retracted, said reciprocable cylinder has its upper end disposed a substantial distance above the lower end of said first mentioned cylinder, and the upper end of said reciprocable cylinder moving upwardly above the upper end of said first mentioned cylinder when said reciprocable cylinder is in its most advanced position.

18. A drilling apparatus as set forth in claim 15 wherein, when said bottom support is resting against the ground and said reciprocable cylinder is retracted, said reciprocable cylinder has its upper end disposed a substantial distance above the lower end of said first mentioned cylinder, and the upper end of said reciprocable cylinder moving upwardly above the upper end of said first mentioned cylinder when said reciprocable cylinder is in its most advanced position.

19. A drilling apparatus as set forth in claim 15 wherein, when said bottom support is resting against the ground and said reciprocable cylinder is retracted, said reciprocable cylinder has its upper end disposed a substantial distance above the lower end of said first mentioned cylinder, and the upper end of said reciprocable cylinder moving upwardly above the upper end of said first mentioned cylinder when said reciprocable cylinder is in its most advanced position.

20. A drilling apparatus as set forth in claim 15 wherein, when said bottom support is resting against the ground and said reciprocable cylinder is retracted, said reciprocable cylinder has its upper end disposed a substantial distance above the lower end of said first mentioned cylinder, and the upper end of said reciprocable cylinder moving upwardly above the upper end of said first mentioned cylinder when said reciprocable cylinder is in its most advanced position.
